(57) **CLAIM**

The ornamental design for a food container with strainer basket, as shown and described.

DESCRIPTION

FIG. 1 is a top, side and front perspective view of the first embodiment of a food container with strainer basket showing my new design;

FIG. 2 is a bottom, side and rear perspective view thereof; FIG. 3 is a front elevation view, the rear elevation being identical thereto;

FIG. 4 is a right side elevation view, the left side elevation being identical thereto;

FIG. 5 is a top plan view thereof;

FIG. 6 is a bottom plan view thereof;

FIG. 7 is an exploded view of the food container with strainer basket shown in FIG. 1;

FIG. 8 is a top, side and front perspective view of the second embodiment of a food container with strainer basket showing my new design;

FIG. 9 is a bottom, side and rear perspective view thereof; FIG. 10 is a front elevation view, the rear elevation being identical thereto;

FIG. 11 is a right side elevation view, the left side elevation being identical thereto;

FIG. 12 is a top plan view thereof;

FIG. 13 is a bottom plan view thereof; and,

FIG. 14 is an exploded view of the food container with strainer basket shown in FIG. 1.
